CYLINDER ROTATING MECHANISM FOR
REVOLVERS

Mildred Dodge Youker, Los Angeles, Calif., assignor, by mesne assignments, to Malcolm P. Youker, Santa Rosa, Calif.

Application October 14, 1946, Serial No. 703,160

11 Claims. (Cl. 42—67)

1

My invention relates to revolvers, and includes in the objects of my invention are:

First, to provide a revolver which employs a novel mechanism for rotating the cylinder whereby the cylinder is effectively locked in position at the instant of firing.

Second, to provide in a revolver a novel cylinder rotating mechanism which may be adapted for use in either toy or cap shooting pistols or may be arranged for use in cartridge firing or service pistols.

Third, to provide a cylinder rotating mechanism for revolvers which is particularly simple and economical of manufacture as well as effective and dependable in its operation.

With the above and other objects in view as may appear hereinafter, reference is directed to the accompanying drawings in which:

Figure 1 is an elevational view of my revolver as adapted for use as a cap or toy pistol.

Figure 2 is a fragmentary longitudinal sectional view thereof taken through 2—2 of Figure 3.

Figure 3 is a transverse sectional view through 3—3 of Figure 2.

Figure 4 is a fragmentary sectional view through 4—4 of Figure 2.

Figure 5 is a fragmentary sectional view similar to Figure 2 but showing the parts during initial movement of the trigger.

Figure 6 is a fragmentary view taken from the opposite side of the revolver from Figure 5 and showing particularly the construction of the hammer.

Figure 7 is a fragmentary sectional view through 7—7 of Figure 2 showing particularly the cylinder rotating means.

Figure 8 is a fragmentary perspective view also illustrating particularly the cylinder rotating means.

Figure 9 is a composite diagrammatical view showing the relationship of the barrel rotating or thrust member, the cam track and the coacting cam lug elements in their various relative positions in a cycle of operation of the revolver.

My revolver, as illustrated in the drawings, is shown as adapted for use as a cap pistol or toy pistol but the cylinder revolving mechanism which will be described hereinafter is equally adaptable for use in a cartridge firing or service pistol.

As designed for a toy pistol my revolver includes a pair of frame plates 1 and 2 which are complementary. One or both of these plates may be shaped to form a handle 3 and a trigger guard 4. The two plates jointly define a cylinder opening

2

5 and clamp forwardly of the cylinder opening 5 a barrel 6. Suitable screws 7 secure the two frame plates together.

At the forward side of the cylinder opening 5 the frame plates form complementary recesses which receive and hold a journal pin 8 which extends axially into the cylinder opening 5. The journal pin 8 supports a cylinder 9 which is rotatable in the cylinder opening 5 and is, in the case of a toy revolver, shaped to simulate the cartridge containing cylinder 9 of a conventional revolver. For purposes which will be brought out hereinafter the cylinder 9 is capable of limited axial movement on the journal pin 8 within the extremities of the cylinder opening 5. A spring 10 yieldably retains the cylinder 9 in its rearward position.

The breech end of the cylinder 9 forms a striking face 11 which is adapted to receive a conventional toy or cap sheet A shown in some of the figures. The cap sheet is held in place by a ring of cam lugs or minor or supplementary cam elements 12 each of which is beveled on one side. The frame plates 1 and 2 are provided with complementary cam bosses 13 in which are formed depressions 14 shaped to mate with diametrically disposed pairs of cam lugs 12. The arrangement of the cam lugs and the depressions in the cam bosses are such that when they are in proximate registry they cause slight arcuate movement of the cylinder 9 when the cylinder 9 is moved from a forward position to a rearward position. The function of the cam lugs in causing such arcuate movement will be brought out in more detail hereinafter.

The striking face 11 of the cylinder 9 is surrounded by an annular cam track 15 in the form of a channel comprising a circumferentially spaced series of helically sloping cam faces or major or primary cam elements 16 separated by keeper recesses 17. Mounted and guided between the frame plates 1 and 2 for axial movement into and out of the cam track 15 is a cylinder thrust or drive pin 18. The pin 18 is provided with a cross head 19 the extremities of which ride in guide channels 20 formed in the frame plates 1 and 2. The cross head 19 is engaged by a trigger lever 21 journaled at its mid-portion on a trigger pivot 22 extending from one of the frame plates. The trigger lever 21 extends into the trigger guard 4 and terminates in a trigger 23.

A spring 24 so engages the trigger lever 21 as to hold the trigger 23 in a forward position and to hold the drive pin 18 in its rearward or retracted position. A hammer 25 is

journalized between the frame plates 1 and 2 on a pivot 26. The hammer includes a head 27 adapted to engage the striking face 11 and a cocking arm 28 projecting upwardly through an accommodation slot defined between the frame plates 1 and 2. A drive spring 29 is arranged to urge the hammer head 27 toward the striking plate. The hammer 25 carries a trip lever 30 backed by a spring 31. The trip lever 30 is so positioned that when the trigger lever 21 is rotated to thrust the drive pin 18 forwardly, the upper extremity of the trigger lever engages the trip lever 30 in a direction to rotate the hammer head 27 away from the striking face 11. After the hammer has thus been drawn back a predetermined distance the trigger lever 21 clears the trip lever 30 releasing the hammer.

During the forward movement of the cylinder drive pin 18, the pin bears against one of the cam faces 16 so as to rotate the cylinder 9. Just prior to release of the hammer 25, the drive or thrust pin 18 enters a keeper recess 17 and locks the cylinder against rotation in either direction. During the movement of the thrust or drive pin 18 into the keeper recess the hammer is released. Thus, at the time the hammer engages the striking face of the cylinder 9, the cylinder is locked against rotation.

The initial pressure of the drive pin 18 against the cylinder 9 forces the cylinder forwardly or axially until the cam lugs 12 clear the depressions 14. When the trigger is released and the thrust or drive pin 18 is withdrawn from the keeper recess 17, the spring 10 urges the cam lugs 12 into engagement with the depressions 14, and as soon as the drive or thrust pin 18 clears the cam track the cam lugs cause the cylinder 9 to rotate a slight distance to bring the succeeding cam face 16 into position for engagement by the thrust or drive pin 18.

To remove or load a new cap sheet A onto the cylinder 9 it is merely necessary to press the cylinder 9 forwardly against the action of the spring 10 until the lugs 12 clear the depressions 14 and then insert the cap sheet.

If the gun be designed for the firing of cartridges, conventional cartridge chambers are formed in the cylinder 9 and the rear ends of such chambers are arranged so that the detonating heads of the cartridges are exposed for engagement by the hammer.

Many other embodiments of the invention may be resorted to without departing from the spirit of the invention.

I claim:

1. A revolver, comprising: a frame structure; a cylinder journalized therein, an annular cam track in the form of a channel recessed in the breech end of said cylinder, said cam track including a circumferential series of cam faces separated by keeper recesses; and a cam engaging member mounted within said frame structure for movement into and out of said cam track, the slope of said cam faces being such that upon movement of said member into said cam track a partial rotation is applied to said cylinder, said keeper recesses receiving said member upon completion of such partial rotation to lock said cylinder until said member is withdrawn.

2. A revolver, comprising: a frame structure; a cylinder journalized therein, a series of main cam and minor cam elements disposed about a common center at the breech end of said cylinder.

der, said main cam elements extending axially and circumferentially into said cylinder; a member engageable with said main cam elements to effect partial rotation of said cylinder, and means coacting with said minor cam elements when said member is disengaged from said main cam elements to advance said cylinder for coaction between said member and a succeeding main cam element.

3. A revolver as set forth in claim 2 wherein keeper means are interposed between said main cam elements for engagement by said member to lock said cylinder against rotation.

4. A revolver comprising: a rotatable cylinder including a cam track disposed in a circle at its breech end having a series of cam faces shaped to produce partial rotation of the cylinder when subjected to a thrust parallel to the axis of said cylinder, and keeper depressions between said cam faces; a thrust member engageable with said cam faces to rotate said cylinder a predetermined distance and thereupon engageable with said keeper depressions to lock said cylinder against further rotation; means supporting said cylinder for limited axial movement in response to engagement of said thrust member with said cam faces; and means operable by axial movement of said cylinder as said thrust member is withdrawn from said keeper depression to advance said cylinder for coaction between said thrust member and the succeeding cam face.

5. A revolver comprising: a frame structure defining a cylinder opening; a cylinder mounted within said opening and arranged for rotation and axial movement; a circular cam track at the breech end of said cylinder, said cam track having cam faces shaped to produce partial rotation of the cylinder when subjected to thrust parallel to the axis of said cylinder; a thrust member mounted within said face structure and engageable with said cam faces to effect a predetermined partial rotation of said cylinder, and to urge said cylinder axially; and means incorporating the breech end of said chamber and said frame structure operable to advance said cylinder between thrusts of said thrust member to present a new cam face.

6. A revolver comprising: a frame structure; a cylinder axially and rotatably mounted therein; main and supplementary coacting cam and cam engaging means carried by said cylinder and said frame structure; said main means including a reciprocable thrust member carried by said frame structure and cam elements carried by said frame structure, said supplementary means including fixed camming elements on said cylinder and said frame structure engageable upon reciprocation of said cylinder to advance said cylinder thereby to present a succeeding cam.

7. A revolver comprising: a frame structure; a cylinder axially and rotatably mounted therein; main and supplementary coacting cam and cam engaging means carried by said cylinder and said frame structure; said main means including a reciprocable thrust member carried by said frame structure and cam elements carried by said frame structure, said supplementary means including fixed camming elements on said cylinder and said frame structure engageable upon reciprocation of said cylinder to advance said cylinder thereby to present a succeeding cam; and a trigger lever for actuating said thrust member.

8. A toy revolver, comprising: a frame structure; a cylinder journalized therein and capable

of limited axial movement; main and minor cam elements arranged in concentric circles at the breech end of said cylinder; a device carried by said frame for coaction with said minor cam elements; yieldable means normally urging said minor cam elements into engagement with said device to restrain said cylinder against rotation; a thrust member engageable with said main cam elements to effect partial rotation of said cylinder, said thrust member operable to shift said cylinder against said yieldable means to free said minor cam elements.

9. A toy revolver, comprising: a frame structure; a cylinder journaled therein and capable of limited axial movement; primary and secondary cam elements disposed at the breech end of said cylinder; yieldable means tending to hold said cylinder in a rearward position; a thrust member engageable with said primary cam elements and cooperating therewith to effect partial rotation of said cylinder, said thrust member also operable to shift said cylinder forwardly against the action of said yieldable means; and a device carried by said frame engageable with said secondary cam elements to effect supplementary partial rotation of the cylinder as said thrust member is retracted.

10. A toy revolver, comprising: a frame structure; a cylinder journaled therein and capable of limited longitudinal movement; a primary and secondary set of cam elements disposed at the breech end; yieldable means tending to hold said

cylinder in an axially rearward position; a device incorporated in said frame structure engageable with said secondary set of cam elements as said cylinder is moved rearwardly to effect partial rotation of said cylinder and thereupon to restrain said cylinder against rotation; and a thrust member mounted in said frame structure and engageable with said primary cam elements, said thrust member moving said cylinder forwardly to free said secondary cam elements from said device and thereupon to cooperate with said primary cam elements to effect partial rotation of said cylinder.

11. A toy revolver as set forth in claim 10 wherein: said primary cam elements are in the form of recesses in said cylinder and each element terminates in a socket receiving said thrust member to lock said cylinder against rotation until said thrust member is withdrawn.
